UNITED STATES PATENT OFFICE.

JOSEPH E. JULIEN AND ERNEST BEAUDOIN, OF LEOMINSTER, MASSACHUSETTS.

DESIGN FOR A HAT-HOLDER PIN.

No. 39,137.

Specification for Design.

Patented Feb. 18, 1908.

Application filed March 8, 1906. Serial No. 305,003. Term of patent 3½ years.

To all whom it may concern:

Be it known that we, JOSEPH E. JULIEN and ERNEST BEAUDOIN, citizens of the United States, residing at Leominster, in the county of Worcester and State of Massachusetts, have invented a new, original, and ornamental Design for a Hat-Holder Pin, of which the following is a specification, reference being had to the accompanying drawings, forming a part thereof.

In the drawings, Figure 1, is a front view

showing our new design; and Fig. 2 is a side view thereof.

We claim—

The ornamental design for a hat holder pin, as shown.

JOSEPH E. JULIEN.
ERNEST BEAUDOIN.
